222,910

COMBINED MAGNETIC TAPE AND TAPE REEL THEREFOR

Reinhold M. Weiss, Chicago, and T. Michael Dennehey,
La Grange, Ill., assignors to Memorex Corporation

Filed Sept. 14, 1970, Ser. No. 24,978

Term of patent 14 years

Int. Cl. D14—01; D16—07

U.S. Cl. D26—14

FIG.
1.

FIG. 2. FIG. 3.

FIG. 4.

FIG. 1 is a perspective view of a combined tape reel and tape reel therefor showing my new design;

FIG. 2 is a side elevational view thereof, the other side being substantially an inverted mirror image thereof;

FIG. 3 is a side sectional view thereof, in a direction indicated by the arrows 3—3 of FIG. 2; and

FIG. 4 is a bottom plan view thereof.

We claim:

The ornamental design for a combined magnetic tape and tape reel therefor, as shown.
